UNITED STATES PATENT OFFICE.

CHARLES L. HURD, OF NEWBURYPORT, MASSACHUSETTS.

FOLDING UMBRELLA.

SPECIFICATION forming part of Letters Patent No. 254,218, dated February 28, 1882.

Application filed December 15, 1881. (No model.)

To all whom it may concern:

Be it known that I, CHARLES L. HURD, of Newburyport, of the county of Essex and State of Massachusetts, have invented a new and useful Improvement in Folding Umbrellas; and I do hereby declare the same to be described in the following specification and represented in the accompanying drawings, of which—

10 Figure 1 is a vertical section of one of my improved umbrellas as it appears when in an open or unfolded state ready for use. Fig. 2 is a section, on an enlarged scale, of one of its ribs, with its rods folded together and upward 15 alongside of the upper section of the stick. Fig. 3 is a longitudinal section of the hinge-joint of the two rods of each rib. Fig. 4 is a view of the umbrella as folded in a compact state to admit of it being carried in an ordinary valise or a carpet-bag.

The nature of my invention is defined in the claim hereinafter presented.

In the said drawings, A denotes the stick; B B, the ribs; C C, the braces; D, the hinge-ring of the ribs; E, the runner of the braces, and F the cloth covering, the latter being formed or made and applied to the ribs in the usual manner.

In carrying out my invention each rib is 30 made of two rods, a b, hinged together, as shown at e, so that the lower one may be turned upward and outwardly alongside of the upper, while its upper end is to be hinged to the stationary ring D in manner to enable such upper rod to be turned through an arc of one hundred and eighty degrees, or thereabout, or from down alongside of the median section of the stick upward alongside of the upper section thereof.

40 The hinge of the two rods of each rib is to be so constructed that when the said rods are in line with each other such hinge will prevent the lower rod from being turned under and up alongside of the upper rod, or between it and the stick. For this purpose, when the two rods are in line with each other, the end part, e', of the upper one abuts against a stop, d, arranged in the hinge portion of the lower one.

The stick A is in three sections, e, f, and g, 50 the latter one of them being provided with a handle, h, and an annular rib fastening slide, i,

if desirable. These sections are connected together by two links, k, arranged between and pivoted to them, and such sections are provided with two tubular slides, l m, to slide upon the stick, so as to cover or uncover the links and hold the sections of the stick in alignment with each other, all being so that when the slides l m are off the links the lower section, g, may be turned upward alongside of the median section, f, and both be turned upward alongside of the upper section, e. The said upper section has the rib hinge-ring D fixed upon and to it, the section with its hinge-link projecting a short distance below the ring D— 65 that is, far enough for the brace-runner E to be slid up to the ring D, and between it and the said link. The runner has a diameter sufficiently larger than that of the hinge-ring to allow of the braces being folded upward about 70 such ring, and alongside of the upper sections of the ribs hinged to such ring.

Spring-catches G H, formed as shown, are applied to the median and lower sections of the stick, such catches being to operate with 75 the brace-runner in holding the umbrella either open or closed, when the slides of the stick are covering the links and holding the stick-sections in line with each other.

An umbrella so made can be folded in a peculiar manner—that is to say, each of the lower rods of each rib can be turned upward alongside of its fellow upper rod, and both be turned upward alongside of the upper section of the stick, the brace-runner being in the meantime 85 moved upward to the hinge-ring D, so as to allow or cause the braces to fold down alongside of the upper rods of the ribs, the cloth covering being folded together with and between the rib-rods. The cloth covering and 90 ribs being so folded relatively to the upper section of the stick, the median and lower sections of it may be folded together and alongside of the folded ribs and covering, thus bringing the whole into a small compass, or into a 95 state for being packed in a valise or hand-bag, or in a short case, as occasion may require.

From the above it will be seen that there are important differences between my folding umbrella and that represented and described in 100 the United States Patent No. 158,994, dated January 19, 1875, and granted to Uriah G.

Steinmetz. The parts of this latter umbrella cannot be folded with respect to the stick, as can the parts of my umbrella, which, when folded, in no respect fold below the upper joint 5 of the stick, but up alongside of and about the uppermost section of the stick, the lower rods of the ribs, when the umbrella is folded, going between the upper rods and the upper section of the stick. In the Steinmetz umbrella, when 10 folded, the upper rods of the ribs are down alongside of the middle section of the stick, and between it and the lower rods of such ribs. In my umbrella the middle section of the stick folds upward alongside of the ribs, and the 15 cloth folds upward alongside of the upper section of such stick, the handle-section being turned downward; but in the Steinmetz umbrella the middle section of the stick folds against the upper section, and not against the 20 ribs and cloth. Furthermore, in my umbrella the brace-runner has a diameter sufficiently larger than that of the hinge-ring to allow of the braces being folded upward about such ring and alongside of the inner section of the ribs when such are folded up alongside of the upper section of the stick; but in the Steinmetz umbrella the hinge-ring, by having a 25 diameter greater than that of the runner, effectually prevents both braces and ribs from being turned upward when the runner is raised 30

up to the said ring. With my improvement the umbrella, when folded, becomes much shorter than that of Steinmetz, because then all the stick that may be above the hinge-ring comes between the ribs and braces; but when 35 the ribs fold downward against the stick such part necessarily projects beyond the braces and the inner sections of the ribs.

I claim—

In a folding umbrella having its stick and 40 each of its ribs in sections jointed or connected together as described, the brace-runner having a diameter larger than that of the hinge-ring, in combination with the ribs hinged to the said ring and the braces to the runner and inner 45 sections of the ribs, and with the outer sections of such ribs connected with the inner sections thereof, so as to be capable of being turned upward over alongside of them, all being substantially as set forth, in order that the ribs 50 and braces may be turned upward alongside of each other and the upper section of the stick, and the outer sections of the ribs be turned in between the stick and the inner sections of such ribs, as explained.
